IRONING MACHINE

John T. Hume, Chicago, Ill., assignor to Electric
Household Utilities Corporation, Chicago, Ill.,
a corporation of Illinois

Application January 12, 1929. Serial No. 332,062

15 Claims. (Cl. 68—9)

This invention relates to improvements in ironing machines and its purpose is to provide an improved and simplified form of ironing machine which may be manufactured at a relatively small cost and used in homes for the ironing of clothes and the like. Heretofore, ironing machines have usually been rather large and somewhat complicated so that their cost has prevented their use in many households and it is, therefore, the principal object of the present invention to provide a relatively small and inexpensive form of ironing machine which is particularly adapted for household use because of its relatively small cost and because of the comparatively small space it occupies. A further object of the invention is to provide an ironing machine of a portable nature which may be moved about and supported on a table or the like when in use. A further object of the invention is to provide an ironing machine of simplified form comprising improved means for rotating an ironing roll and for effecting relative movement of an ironing shoe and the ironing roll. Still another object is to provide an improved ironing machine comprising means for controlling the operation of the roll and for controlling the movement of the shoe toward and from the roll. Other objects relate to various features of construction and arrangement which will appear more fully hereinafter.

The nature of the invention will be understood from the following specification taken with the accompanying drawings, in which one embodiment is illustrated. In the drawings,

Figure 1 shows a top plan view of the improved ironing machine;

Fig. 2 shows a front elevation thereof;

Fig. 3 shows an end elevation, looking toward the left as viewed in Fig. 2;

Fig. 4 shows a vertical detail section through the ironing shoe and its support on the line 4—4 of Fig. 1;

Fig. 5 is an enlarged detail vertical section through the housing of the ironing machine and the parts contained therein, on the line 5—5 of Fig. 1;

Fig. 6 is an enlarged detail sectional view taken on the line 6—6 of Fig. 1;

Fig. 7 is a horizontal detail sectional view taken on the line 7—7 of Fig. 5;

Fig. 8 is a horizontal section taken longitudinally through the roll and driving mechanism of the ironing machine on the line 8—8 of Fig. 5; and

Fig. 9 is an enlarged detail section, similar

to that of Fig. 8, showing a portion of the driving mechanism of the roll and the clutch mechanism for controlling the operation of the roll.

As illustrated in the accompanying drawings, the invention comprises a supporting base or plate 10 which is adapted to rest upon a table or other support 11 and which is preferably provided with a suitable number of rubber cushions 12 or the like for contacting directly with the surface of the table. The frame or housing 14 of the ironing machine is mounted on one end of the base 10 and the lower part of this housing is constructed as a dome-shaped casing 14^a which contacts around its lower edge with the base 10 and is secured thereto by studs 15 extending upwardly through apertures in the base 10 and engaging threaded bosses in the lower part of the frame or housing 14.

The housing 14 has an upward extension 14^b, as shown in Fig. 6, which is provided, as illustrated in Fig. 8, with an annular horizontal extension 14^c. Within the part 14^c there is mounted a fixed hollow shaft or axle 16 upon which the ironing roll 17 is rotatably mounted. The axle 16 projects longitudinally from the housing 14 above and parallel to the base 10 in such a position that the lower peripheral portion of the ironing roll 17 is disposed some distance above the upper surface of the base. The roll 17 comprises two sheet metal disks 18 provided with longitudinally directed annular flanges 18^a having bushings 19 mounted therein and journaled on the axle 16. At the outer edges, the disks 18 are directed outwardly in the form of longitudinal flanges 18^b which are united with 90 and closely fit the inner surface of the metal cylinder 20 which forms the frame structure of the roll 17. Upon this metal cylinder 20, there is wound a suitable number of layers of fabric 21 to serve as the medium for contacting directly with the clothes being ironed. At the outer end of the roll 17, the disk 18 is provided with an aperture 22 which is detachably engaged by a pin 23 mounted in a driving member 24. This driving member is slotted to receive the pin 23 and is provided with a recess in which there is mounted a coil spring 25 adapted to force a spherical ball 26 into a groove 23^a in the pin for holding it in its inner engaging position as shown in Fig. 8. The pin 23 has a pin 23^b by 95 which it may be withdrawn to disengage the driving member 24 from the disk 18.

The driving member 24 is secured by a set screw 28 on a driving shaft 30 and the driving member 24 is further provided with an inwardly 100

110

extending hub 24^a having a bushing 31 thereon which is journaled in the outer end of the axle 16, thus supporting the driving member 24 and also the outer end of the driving shaft 30. The 5 inner end of the driving shaft is journaled in the hub 32^a of the driving gear 32 and this hub 32^a is provided with a bushing 33 which is in turn journaled within the inner end of the stationary axle 16. When a driving connection is established 10 between the gear 32 and the shaft 30, the roll 17 is rotated, assuming that the pin 23 is in the engaging position shown in Fig. 8. The gear 32 is driven by a spiral gear 34 which extends vertically within the portion 14^b of the 15 housing, as shown in Fig. 5, and which is journaled at its upper and lower ends in the bearings 35 and 36, respectively, which are carried in suitable apertures formed in the housing. The lower bearing member 36 has a threaded engagement 20 with an aperture in the housing and is provided with recesses 36^a for engagement by the prongs of a suitable wrench so that it may be turned into proper position after the shaft of the spiral gear 34 is in place. The shaft of the spiral gear 25 34 carries another spiral gear 37 which meshes with a spiral gear 38 mounted on an intermediate shaft 39. This shaft 39 is journaled in bearings 40 and 41 which are mounted in the walls of the casing, the latter bearing member 41 having a 30 threaded engagement with the casing so that it may be removed to permit the withdrawal of the shaft 39. The shaft 39 has fixed thereon or formed integrally therewith another spiral gear 42 which meshes with a spiral gear 43 secured on 35 the shaft 44 of an electric motor 45 which provides the driving power for the ironing machine. The motor 45 is mounted within the lower portion 14^a of the housing 14 and is secured in place by a threaded engagement of the hub 46 thereof 40 with an aperture which is formed in the wall 47 separating the lower portion of the housing 14 from the upper portion 14^b thereof, as illustrated in Fig. 6. The hub 46 is provided with a roller bearing 48 in which the shaft 44 of the motor is 45 mounted and, by the arrangement just described, the casing of the motor 45 is suspended from the division wall 47 of the housing 14 with the axis of the shaft 44 extending vertically. A nut 49 serves to secure the spiral gear 43 in its place 50 splined on the shaft 44. An opening 15^a is provided in the base 10 to permit access to the motor 45 from beneath the base. After the motor has been disengaged from the division wall 47, it 55 may be removed from the housing 14 by withdrawing the studs 15 which secure the housing to the base 10.

The electric motor 45 is connected in a suitable electric circuit and when this circuit is closed, the driving gear 32 is operated continuously. For 60 the purpose of controlling the operation of the driving shaft 30 by the gear 32, certain clutch mechanism is provided comprising an inner clutch member 50 which is secured on the projecting end of the shaft 30 by a transverse pin 65 51. This clutch member is provided with longitudinal teeth which form a sliding driving engagement with similar teeth on an outer clutch sleeve 52. This clutch sleeve is provided at one end with an annular series of clutch teeth 53 70 which are adapted to mesh with the teeth of a clutch member 54 secured to the face of the gear 32 by means of rivets 55. When the clutch member 52 is in its inner position, as shown in Fig. 8, the clutch teeth 53 and 54 are in engagement and 75 a driving connection is then established between

the gear 32 and the driving shaft 30. The outer end of the clutch member 52 is secured to a circular plate 56 having its center attached to a plunger 57 which extends into the bore 58 of a shaft 59 which is rotatably mounted in the detachable end cap 60 of the housing 14. A coil spring 61 is mounted in the bore 58 and serves normally to force the plunger 57 toward the left as viewed in Figs. 8 and 9, thereby tending normally to cause the clutch teeth 53 to engage the clutch member 54 mounted on the gear 32. The movement of the clutch member 52 to the disengaged position shown in Fig. 9 is effected by means of a bell-crank lever 63 which is pivoted at 64 on a bracket 65 attached to the housing 14 by means of a set screw 66. The bell-crank lever is provided with a bifurcated arm 63^a which straddles the clutch member 52 and the ends of this bifurcated arm are adapted to engage the annular flange 52^a formed on one end of the clutch member when the other arm 63^b of the bell-crank lever is depressed, thereby disengaging the clutch teeth. The depression of the arm 63^b of the bell-crank lever 63 is brought about by engagement of a cam 70 with a roller 71 which is rotatably mounted on the end of the arm 63^b. This cam 70 is keyed on the shaft 59 previously described and the end of this shaft is provided with a transverse bore 72 formed in the enlarged head 59^a to receive an operating handle 73 which slidably engages this bore and which is adapted to be held in the desired position therein by means of a ball 74 which is pressed by the coil spring 75 to engage one of the annular grooves 73^a which are formed in the handle 73. Upon turning the handle 73, the bell-crank lever may be operated to disengage the clutch teeth and thereby permit the driving gear 32 to rotate without rotating the shaft 30 by which the roll 17 is driven. 80

The ironing shoe 77, which is adapted to contact with the ironing roll 17, is shown particularly in Figs. 4, 5 and 6 where it is illustrated as including a metal plate 78 of substantially the same length as the roll 17 and provided on its inner side with a concave surface 78^a adapted 85 to conform to the curvature of the external cylindrical surface of the roll 17. The upper and lower edges of the plate 78 are provided with flanges 78^b which are adapted to hook over the supporting plate 79 which has a similar curvature 90 and which is of substantially the same length. This plate 79 is mounted upon a supporting bracket 80 and it is spaced from the plate 78 to form an intervening heating chamber 81 in which is located a heating element 82 comprising an 95 electric conductor located between sheets of insulating material or embedded in insulating material and spaced from the rear supporting plate 79 by means of a body 83 of insulating material. The electrical conductor of the heating element 82 is connected in an electric circuit to a fitting 84 which is mounted upon one end of the shoe, as shown in Fig. 2, and which contains suitable terminals connected to the electric conductors 85. These conductors 85 and other 100 branch conductors 86 lead from supply conductors 88 which are connected in an electric circuit through the usual connecting plug 89. The branch conductors 86 are connected to the terminals of the electric motor 45 and flow of current through the branch conductors 85 to the heating element of the shoe is controlled by a switch 87 mounted on a part of the housing 14 and controlled by an operating handle 87^a. 105

The shoe 77 is carried by a supporting arm 90 110

which is provided at its upper end with a hub 90^a mounted to extend between the arms of the bracket 80 from which it is spaced by collars 91. A bolt 92 extends through the arms of the bracket 80 and through the hub 90^a from which it is spaced by a bushing 93 and this bolt is secured in place by a nut 95 engaging the threaded end thereof. The shoe 77 is thus capable of pivotal movement on the supporting arm 90 and it is caused to maintain the normal condition shown in Figs. 4 and 5 by means of a leaf spring 96 which is secured to the arm 90 by a screw 97 and which extends around the hub 90^a with its free end directed downwardly and engaging the flange 78^b at the lower edge of the shoe, as shown in Fig. 4. This normal position of the shoe 77 is such that when the arm 90 is moved to cause the shoe 77 to engage the roll 17, the lower edge of the plate 78 engages the roll 17 before the upper portions of the shoe engage the roll. The ironing shoe thus has a progressive engagement with the roll from its lower edge upwardly as the shoe is moved toward the roll by a rocking movement of the supporting arm 90 and this is adapted to insure the ironing of clothes in case portions of the clothes are projected between the shoe and the roll before the shoe is brought entirely into engagement with the roll or the clothes to be ironed. The lower end of the supporting arm 90 is provided with a bifurcated hub 90^b provided with a pair of projecting ears 98 engaged by a threaded stud 99 so that the supporting arm 90 may be clamped securely on the end of a hollow shaft 100, as shown in Fig. 4. This hollow shaft 100 is journaled in bushings 101 which are fixed within a hollow axle 102 illustrated particularly in Fig. 8. This hollow axle is secured within the rear extension 14^b of the housing 14 by which the roll 17 is carried. The outer end of the hollow shaft 100 is closed by a plug 103 and the split hub 90^b closely engages the outer end of the hollow axle 102.

The inner end of the hollow shaft 100 projects beyond the inner end of the hollow axle 102 into the chamber 104 of the housing extension 14^b, this chamber being normally closed by a detachable cover 105. This projecting extremity of the hollow shaft 100 is provided with a transverse slot in which there is fixed a pin 106 of rectangular cross-section which maintains the shaft 100 against longitudinal displacement in the hollow axle 102 and also provides means whereby the shaft may be rotated to move the shoe 77 into and out of engagement with the roll 17. The pin 106 has a projecting rounded extremity 106^a, shown in Fig. 6, which engages a recess 107^a formed in one side of a cylindrical block 108 which is mounted to slide in the cylindrical portion 14^c of the housing 14 which connects the rear extension 14^d with the upper portion 14^b of the housing. The block 108 is mounted for sliding movement on a plunger 109 which is united at its upper end with a piston 110 mounted to slide in the cylindrical casing 14^c. This piston 110 is held against rotation in the cylinder 14^c by means of a set screw 111 which engages a groove 112 formed in one side of the piston. This piston is further provided with a pair of projecting ears 112^a between which extends a pin 113 of circular cross-section upon which is mounted a roller 114. This roller is adapted to engage the face 70^b of the cam 70 previously described, this face being located opposite to the face 70^a which is engaged by the roller 71 for operating the clutch lever 63. A coil spring 115 is mounted around the plunger 109 between the piston 110 and the block 108 and this spring tends normally to force the block 108 toward the right as viewed in Fig. 6. The lower end of the plunger 109 is reduced in cross-section as shown in 109^a and 80 is engaged by a washer 116 which seats against the shoulder at the end of the body portion of the plunger to limit the downward movement of the block 108. A nut 117 engages the threaded lower extremity of the plunger 109 to hold the washer 116 in place and the coil spring 118 engages the washer 116 and surrounds the nut 117 with its lower end engaging a recess 119^a formed in the cap member 119. This cap member 90 threadedly engages the lower end of the housing extension 14^c and may be adjusted to vary the compression of the spring 118 which normally forces the plunger 109 in an upward direction to maintain the roller 114 in close contact with the cam surface 70^b. When the handle 73 is operated to rotate the cam 70 to a position wherein the cam surface 70^b and the bell crank lever 63 permit the clutch member 52 to be thrown into driving position by the action of the coil spring 61, the rotation of the cam 70 operates simultaneously, through the cam surface 70^b, to force the plunger 109 toward the right, as viewed in Fig. 6, thereby transmitting motion through the coil spring 115 to the pin 106 so that the hollow shaft 100 is rotated to rock the supporting arm 105 and thereby move the shoe 77 into engagement with the roll 17, as shown in Fig. 6. When the operating handle 73 is turned to a position wherein the cam 70 disengages the clutch 52 by the operation of the bell crank lever 63, thereby 110 arresting the rotation of the ironing roll 17, the ironing shoe 77 is simultaneously disengaged from the roll, thereby preventing the burning of the clothes or of the roll, due to the fact that the block 108 and the plunger 109 are then forced 115 upwardly and toward the left, as viewed in Fig. 6, by the action of the coil spring 118, thus turning the hollow shaft through the pin 106 and moving the ironing shoe 77 to the position shown in Fig. 5. The cam surface 70^b is of such configuration that it accommodates this movement of the shoe as the roller 114 passes along the cam surface from engagement with one extremity of the cam surface to the depression at the other end thereof. A single cam operated by a single 120 controlling arm or lever is thus employed for controlling the engagement and disengagement of the clutch which actuates the roll and also for controlling the movement of the ironing shoe toward and from the roll. By this means, the 125 separation of the shoe and roll is insured when the roll 17 is not being rotated through the clutch by the driving motor.

It will be apparent that the foregoing invention provides an ironing machine of compact and 130 simple form which may be cheaply manufactured and readily assembled and which embodies features which enable it to be operated conveniently and safely by persons who are not skilled in the operation of machinery. An electric switch in a 135 convenient location serves to control the circuit of both the heating pad of the shoe and a single controlling arm 73 is employed for controlling both the rotation of the roll and the movement 140 of the shoe. This ironing machine may be manufactured in a relatively small size adapted for household use and due to its compact arrangement and the mounting of the housing on a supporting base 10, adapted to be supported on a 145 150

table or the like, the machine may be moved about conveniently and stored in a relatively small space when not in use.

Although one form of the invention has been shown and described by way of illustration, it will be understood that it may be constructed in various other embodiments within the scope of the appended claims.

I claim:

- 10 1. The combination in a household ironing machine, of a portable base adapted to rest upon an elevated support, a tubular housing secured to one end of said base and extending upwardly therefrom to form a supporting column, ironing elements carried by said housing and extending endwise therefrom over said base, a driving motor mounted within said housing above said base, a vertical shaft within said housing driven by said motor, driving connections between said shaft and one of said ironing elements, and means operated from the outside of said housing for controlling said driving connections.
- 15 2. The combination in a household ironing machine, of a portable base adapted to rest on an elevated support, a tubular housing secured on said base and extending upwardly therefrom to form a supporting column, an ironing roll and a shoe carried by said housing, actuating mechanism mounted in the upper part of said housing for rotating said roll, and a driving motor mounted in the lower part of said housing with its shaft extending vertically and operably connected to said mechanism.
- 20 3. The combination in a household ironing machine, of a portable base, a tubular housing mounted on said base and extending upwardly therefrom to form a supporting column, said base having an aperture therein beneath said housing, a motor mounted in said housing above said aperture, driving mechanism mounted in the upper part of said housing and actuated by said motor, and an ironing roll carried by said housing for operation by said mechanism.
- 25 4. The combination in an ironing machine, of a portable base, a housing mounted upon one end of said base and extending upwardly therefrom, an ironing roll and an ironing shoe carried entirely by said housing and extending endwise therefrom over said base, said housing having a horizontal division wall, a motor mounted in the lower part of said housing and having its shaft journaled in said division wall, and mechanism located in the upper part of said housing directly above the motor and driven by said shaft for rotating said roll.
- 30 5. The combination in an ironing machine, of a housing, a roll and a shoe carried by said housing and extending endwise therefrom, driving mechanism in said housing for rotating said roll, a clutch for controlling said driving mechanism, a shaft journaled in said housing and having said shoe mounted thereon, a compressible operating device slidably mounted in a part of said housing and connected to said shaft for effecting a rocking movement thereof, a cam adapted to effect movement of said operating device, means operated by said cam, to control the operation of said clutch, and means for rotating said cam.
- 35 6. The combination in an ironing machine, of a housing, an ironing roll carried by said housing, a shoe for cooperation with said roll, a rock shaft having said shoe mounted thereon, said housing having a tubular part, a block slidably mounted in said tubular part and having a connection with said rock shaft for effecting angular movement thereof, and means including a cam for effecting longitudinal movement of said block.
- 40 7. The combination in an ironing machine, of a housing, an ironing roll carried by said housing, a shoe for cooperation with said roll, a rock shaft having said shoe mounted thereon, said housing having a tubular part, a block slidably mounted in said tubular part and having a connection with said rock shaft for effecting angular movement thereof, an operating member resiliently connected with said block and having a roller mounted thereon, and a cam to cooperate with said roller for effecting longitudinal movement of said operating member and said block.
- 45 8. The combination in an ironing machine, of a housing, an ironing roll carried by said housing, a shoe for cooperation with said roll, a rock shaft having said shoe mounted thereon, said housing having a tubular part, a block slidably mounted in said tubular part and having a connection with said rock shaft for effecting angular movement thereof, a plunger slidably mounted in said casing and having a sliding engagement with said block, a spring interposed between said plunger and said block, and a cam adapted to effect longitudinal movement of said plunger and said block.
- 50 9. The combination in an ironing machine, of a housing, an ironing roll carried by said housing, a shoe for cooperation with said roll, a rock shaft having said shoe mounted thereon, said housing having a tubular part, a block slidably mounted in said tubular part and having a connection with said rock shaft for effecting angular movement thereof, a plunger slidably mounted in said casing and having a sliding engagement with said block, a spring interposed between said plunger and said block, a roller mounted on said plunger, a cam cooperating with said roller for effecting longitudinal movement of said plunger and said block, and a second spring engaging said plunger independently of said block for maintaining said roller in contact with said cam.
- 55 10. The combination in an ironing machine, of a housing, an ironing roll carried by said housing, a shoe for cooperation with said roll, a rock shaft having said shoe mounted thereon, said housing having a tubular part, a block slidably mounted in said tubular part and having a connection with said rock shaft for effecting angular movement thereof, a plunger slidably mounted in said tubular part and having a sliding engagement with said block, a spring interposed between said plunger and said block, a roller mounted on said plunger, a cam cooperating with said roller for effecting longitudinal movement of said plunger and said block, a second spring engaging said plunger independently of said block for maintaining said roller in contact with said cam, and means for adjusting the tension of said last-named spring.
- 60 11. The combination in an ironing machine, of a housing, an ironing roll carried by said housing, said housing having a tubular extension extending therefrom transversely to said roll, a hollow axle extending parallel to said roll and carried by said tubular extension, a rock shaft journaled in said axle, a shoe mounted on said rock shaft, an operating device slidably mounted in said tubular extension for actuating said rock shaft, and means located in said housing for actuating said operating device and controlling the rotation of said roll.
- 65 12. The combination in a household ironing machine, of a portable base plate adapted to rest upon a table, a tubular housing secured on said

thereof, and means including a cam for effecting longitudinal movement of said block.

7. The combination in an ironing machine, of a housing, an ironing roll carried by said housing, a shoe for cooperation with said roll, a rock shaft having said shoe mounted thereon, said housing having a tubular part, a block slidably mounted in said tubular part and having a connection with said rock shaft for effecting angular movement thereof, an operating member resiliently connected with said block and having a roller mounted thereon, and a cam to cooperate with said roller for effecting longitudinal movement of said operating member and said block.

8. The combination in an ironing machine, of a housing, an ironing roll carried by said housing, a shoe for cooperation with said roll, a rock shaft having said shoe mounted thereon, said housing having a tubular part, a block slidably mounted in said tubular part and having a connection with said rock shaft for effecting angular movement thereof, a plunger slidably mounted in said casing and having a sliding engagement with said block, a spring interposed between said plunger and said block, and a cam adapted to effect longitudinal movement of said plunger and said block.

9. The combination in an ironing machine, of a housing, an ironing roll carried by said housing, a shoe for cooperation with said roll, a rock shaft having said shoe mounted thereon, said housing having a tubular part, a block slidably mounted in said tubular part and having a connection with said rock shaft for effecting angular movement thereof, a plunger slidably mounted in said casing and having a sliding engagement with said block, a spring interposed between said plunger and said block, a roller mounted on said plunger, a cam cooperating with said roller for effecting longitudinal movement of said plunger and said block, and a second spring engaging said plunger independently of said block for maintaining said roller in contact with said cam.

10. The combination in an ironing machine, of a housing, an ironing roll carried by said housing, a shoe for cooperation with said roll, a rock shaft having said shoe mounted thereon, said housing having a tubular part, a block slidably mounted in said tubular part and having a connection with said rock shaft for effecting angular movement thereof, a plunger slidably mounted in said tubular part and having a sliding engagement with said block, a spring interposed between said plunger and said block, a roller mounted on said plunger, a cam cooperating with said roller for effecting longitudinal movement of said plunger and said block, a second spring engaging said plunger independently of said block for maintaining said roller in contact with said cam, and means for adjusting the tension of said last-named spring.

11. The combination in an ironing machine, of a housing, an ironing roll carried by said housing, said housing having a tubular extension extending therefrom transversely to said roll, a hollow axle extending parallel to said roll and carried by said tubular extension, a rock shaft journaled in said axle, a shoe mounted on said rock shaft, an operating device slidably mounted in said tubular extension for actuating said rock shaft, and means located in said housing for actuating said operating device and controlling the rotation of said roll.

12. The combination in a household ironing machine, of a portable base plate adapted to rest upon a table, a tubular housing secured on said

- base and extending upwardly therefrom to form a supporting column, an ironing roll and a shoe carried by said housing and extending endwise therefrom over said base plate, actuating mechanism mounted in said housing for rotating said roll, a driving motor mounted in the lower part of said housing and having its shaft extending upwardly therefrom to operate said actuating mechanism, and manually controlled means for 10 moving said shoe and controlling the operation of said mechanism by said shaft.
13. The combination in a household ironing machine, of a portable base plate adapted to rest upon a table, a housing mounted on said base plate, an ironing roll carried by said housing and projecting endwise therefrom over said base plate, said housing having a tubular extension extending therefrom transversely to the axis of said roll, a rock shaft carried by said tubular extension and 20 extending parallel to said roll, an ironing shoe carried by said rock shaft, a device movable in said tubular extension for actuating said rock shaft, and means located in said housing for operating said device and rotating said roll.
25. 14. The combination in a household ironing machine, of a portable base plate adapted to rest upon a table, a tubular housing secured on said base plate and extending upwardly therefrom, an ironing roll and a shoe carried by said housing and extending horizontally therefrom over said base plate, a rock shaft extending from said housing and having said shoe mounted thereon, said housing having a tubular part, a block slidably mounted in said tubular part and having a connection with said rock shaft for effecting angular movement thereof, and means for effecting longitudinal movement of said block. 80
15. The combination in a household ironing machine, of a portable base plate adapted to rest upon a table, a tubular housing secured on said base plate and extending upwardly therefrom, an ironing roll and a shoe carried by said housing and extending horizontally therefrom over said base plate, a rock shaft extending from said housing and having said shoe mounted thereon, said housing having a tubular part, a block slidably mounted in said tubular part and having a connection with said rock shaft for effecting angular movement thereof, a plunger slidably mounted in said casing and having a sliding engagement with said block, a spring interposed between said plunger and said block, and a cam adapted to effect longitudinal movement of said 100 plunger and said block. 85
